UNITED STATES PATENT OFFICE.

EDWIN G. RUST, OF PUEBLO, COLORADO.

VALVE MECHANISM FOR BLOWING-ENGINES.

SPECIFICATION forming part of Letters Patent No. 766,732, dated August 2, 1904.

Application filed May 13, 1902. Serial No. 107,113. (No model.)

To all whom it may concern:

Be it known that I, EDWIN G. RUST, a citizen of the United States, and a resident of Pueblo, Colorado, have invented certain Improvements in Valve Mechanism for Blowing-Engines, of which the following is a specification.

My invention relates to certain improvements in valve-operating mechanism, and more particularly consists in an improved arrangement of parts for use in connection with the compressing-cylinder of an engine especially designed for supplying air or gas under pressure.

The object of my invention is to provide a device of the character described in which the dead-space or clearance in the compressing-cylinder is reduced to a minimum, the construction being such that the inlet and the discharge valves are balanced.

20 A further object of the invention is to provide means whereby the point of opening of the discharge-valves, and therefore the pressure at which the air is delivered, may be varied at will.

25 Another object of the invention is to provide mechanism connected to the discharge-valve for automatically indicating the opening position of said valve, and therefore the pressure at which the air is being delivered from the compressor.

These objects I attain as hereinafter set forth, reference being had to the accompanying drawings, in which—

Figure 1 is a side elevation, partly in section, 35 of an engine and its compressor, illustrating the valve-gear and my improved arrangement of inlet and discharge valves. Fig. 2 is a slightly-enlarged plan view of the upper portion of the compressor-cylinder shown in Fig.

40 1. Fig. 3 is a sectional elevation through the compressor-cylinder and the admission and discharge valves, the same being taken on the line 3 3, Fig. 2; and Fig. 4 is a sectional elevation, on an enlarged scale, of a portion of the mechanism shown in Fig. 3, the same illustrating in detail the construction of one of the inlet-valves with its corresponding discharge-valve.

In the above drawings, A is the main frame 50 of the engine proper, which is shown of the

vertical type and is provided with a steam-cylinder A' of any desired construction. Carried upon said cylinder is the compressor-cylinder B, in which operates a piston B⁵, connected, by means of a piston-rod *b*, to the piston (not shown) within the engine-cylinder, it being understood that the engine is provided with piston and connecting rods, which are connected to the main shaft *a* in the well-known manner common to engines. 55

In addition to the necessary mechanism for operating the engine there is an eccentric *a'* for operating the air-valve mechanism provided with a strap *a²*, held by means of a link *a³* to a fixed point on the engine-frame and 65 provided with a slotted projection *a⁴*, the whole forming what is known as an "Allen link," it being understood that while such link-motion is a very desirable form I do not confine myself to the same, since there are others by 70 which the same results can be obtained—as, for example, the Marshall.

It will be seen that each of the ends or heads of the compressor-cylinder is provided with two sets of inlet and discharge valves, each set 75 consisting of a single inlet and a single discharge valve, as shown in Fig. 3. These valves are preferably operated from two independent wrist-plates *b'* and *c'*, (shown by dotted lines in Fig. 1,) the first of these, which operates the inlet-valves, being connected, through a rod *b³*, lever *b⁴*, rod *b⁵*, bell-crank lever *b⁶*, and link *b⁷*, to a point on the strap *a²* on the eccentric. The second of the wrist-plates *c'*, which operates the discharge-valves, is connected, through the rod *c³*, lever *c⁴*, and rod *c⁵*, to a block *c*, sliding in a slot in the projecting portion *a⁴* of the strap *a²*, forming part of the operating link-motion. 85

A bar *d* extends from near the lower end 90 of the rod *c⁵* to one arm of the bell-crank lever *d'*, the other arm of said lever being connected, by means of a rod *d²*, to a pivoted operating-arm *d³*. One of the arms of the bell-crank lever *d'* is formed into an indicator-point, and there is a scale *d⁴* fastened to the engine-frame and adjacent to said point, for a purpose hereinafter to be described. 95

Passing now to that portion of the valve mechanism upon the compressor-cylinder B, 100

it will be seen that there are projections or standards b^2 from the top and bottom, respectively, of the castings forming the heads of the cylinder B, the said standards carrying 5 spindles or shafts e , which have fixed to them arms e' , connected by links or rods e^2 to the wrist-plate c' . These shafts also have on them cams e^3 , (shown in Figs. 1 and 2,) and there are forked levers e^4 carried upon the standards 10 and b^2 , each having one end pinned to a sliding cross-head o , connected to a valve-rod f , attached to the discharge-valves F, while their forked ends are provided with rollers e^5 , bearing upon the peripheries of the said 15 cams.

From Figs. 3 and 4 it will be seen that the compressor-cylinder has at each end a casting B', forming a head in which is fitted one or more cylindrical cages B², (in the present 20 instance two,) each primarily consisting of inner and outer shells b^8 and b^9 , respectively. The space between the cages B² and the sides of the head B' communicates with the atmosphere through ports or openings f^4 , while 25 there are ports f^2 from the space between the shells b^8 and b^9 into the cylinder B and other ports f^6 and f^7 opening into the space between said shells through the inner and outer shells, respectively. The space between the 30 outer shell b^9 and the cylinder-head casting B' is shut off from the remainder of the interior of the space within said casting by means of a ring b^{10} , and the interior of the cages B² is in communication with this latter space, 35 there being a delivery-pipe B³ formed in each head-casting and a cover B⁴ provided for each of the openings for the admission of the valves and cages.

There is a cylindrical valve F, preferably 40 the discharge-valve, within each of the cages B², controlling the flow of fluid through the ports f' , there being a valve-rod f' for the same which passes through a stuffing-box f^5 in the cover B⁴ and is connected to its appropriate lever e^4 through the sliding cross-head, as above described.

Sliding upon the outside cylindrical shell b^9 of each cage B² is an annular valve G, preferably the inlet-valve, and there are two 50 valve-rods g for every valve passing through tubes g' , extending between the ring b^{10} and the cover B⁴. These rods are pinned to the arms g^2 , projecting from the shaft h and supported on standards h^3 , the said shaft also 55 having an operating-arm h' connected by links or rods h^2 to the wrist-plate b' . It will be seen that the different sets of admission and discharge valves are practically the same in construction, there being any desired number 60 of the same for each cylinder-head.

Both the piston-valves F and the annular valves G have suitable packing-rings f^6 and g^3 , respectively, in their operating-faces and, as shown, are designed to be reciprocated, so 65 as to control the flow of fluid through their

respective ports, the openings from the space between the cage-rings b^8 and b^9 into the compressor-cylinder being common to both of these. From Fig. 1 it will be noted that the connections between the wrist-plate b' and the operating link-motion are practically unchangeable relatively to one another, it being understood that the time of opening and closing the valves G will therefore always be nearly the same relatively to the piston B in 75 the compressor-cylinder. In other words, any one of said valves will always close as soon as the piston begins to move toward it and always open shortly after the piston begins to move away from it. The valve-gear, however, through which the valves F are operated, is so designed and assembled that the said valves always close just as the piston reaches the end of its stroke and open to allow air to 80 pass from the compressor-cylinder at a variable point relatively to the piston-stroke, depending upon the position of the block c in the slotted portion a^4 of the link-motion. By this means, therefore, it will be seen that in 85 operation the mechanism can be adjusted by shifting the block c in its slot through the medium of the links and levers connected to the operating-handle d^3 , so that the discharge-valve is made to open to suit any pressure at 90 which air is being delivered by the compressor. 95

By means of the pointer and scale d^4 , as shown in Fig. 1, I am enabled at a glance to tell the exact position of the discharge-valves relatively to the piston of the compressor or to set said valves so that the air is delivered 100 under any desired predetermined pressure. I preferably calibrate the said scale either by experiment or calculation, so that the position of the pointer can be read as the number of pounds pressure at which the air is being delivered. For example, assuming the engine to be delivering air at five-pounds pressure, the discharge-valve should open just when the air being compressed in the cylinder B is under five-pounds pressure. In order that the 105 discharge-valve F shall begin to open just at this point, the link-block c should be in such a position in the slot a^4 that the pointer on the end of the bell-crank lever d' will point to figure "5" on the graduated scale. Similarly 110 when the compressor is delivering air, say, at ten pounds, the link-block c should be at a definite point in slot a^4 , so that the discharge-valve F will open just when the pressure in the cylinder B has reached ten pounds. When 115 the link-block c is in proper position in the slot a^4 , then the pointer at the end of lever d' will point to "10" on the graduated scale d^4 . Similarly whatever air-pressure is being delivered by the compressor, as indicated by a 120 pressure-gage, the pointer at the end of lever d' being set to a number corresponding to the gage-pressure will place the block c at the proper position in slot a^4 so that the discharge-valve F will open at the proper point 125 130

relative to the position of the piston to deliver air at the particular pressure required. Since these positions of the pointer are always the same for the same pressure, it follows that by 5 manipulating the position of the link-block *c* through the medium of its connections the said block can be so placed in slot *a*⁴ as to cause the discharge-valves *F* to open for any desired pressure which is being delivered by the compressor. The position of link-block *c*, corresponding to this particular pressure of air or 10 gas, is known by means of the pointer at the end of lever *d*⁴ pointing to the number on the graduated scale *d*⁴ corresponding to the said pressure. 15

In Fig. 1 although the graduated scale *d*⁴ is shown attached to the engine-frame opposite the pointer at the end of lever *d*⁴ it will be understood that I do not confine myself 20 to any particular location for this portion of my device, since it might be opposite the operating-lever *d*³, as shown in dotted lines, Fig. 1, or might be placed on the face of the link *a*⁴ or at any other convenient point which 25 can be satisfactorily graduated to indicate the position of the link-block *c*, and hence the pressure of the gas being delivered by the compressor.

Referring to cam *e*³, Fig. 1, I preferably, 30 but not necessarily, operate the discharge-valve through the medium of these cams, whose operating-shaft *e* is connected by lever *e*' and rod *e*² to wrist-plate *c*', which plate is oscillated in the well-known manner. The object of operating these valves by means of a 35 cam-motion is twofold: first, to provide means for taking up the necessary overtravel of the valve-operating mechanism, while limiting the movement of the discharge-valves; second, by 40 means of the cams the discharge-valves will be made both to open and close quickly and have a period of rest at the end of each operation. The inlet-valve I show preferably operated by means of a wrist-plate and lever connections; but I do not limit myself to any 45 special means of operating this valve, which could be operated by means of cams or any other system of levers or by means of any other valve-operating mechanism.

50 It will be noted that by the particular construction of valves and ports above described I am enabled to greatly reduce the necessary clearance-spaces in the heads of the compressor-cylinder, the use of the single set of 55 ports *f*² for both inlet and discharge resulting in a very decided economy of space as well as a simplification of the construction.

It will be further noted that both the inlet and discharge valves are of the "balanced" 60 variety, there being consequently no unnecessary expenditure of energy in operating them and a noticeable decrease in the wear on the several parts.

I claim as my invention—

65 1. The combination in a compressor of a

cylinder, a piston, a head for said cylinder including a structure provided with a plurality of cylindrical surfaces having ports in them, independent inlet and discharge valves coacting with said ports, and operating mechanism 70 connected to the valves, there being also in the head a port or ports opening into the cylinder and placed to serve as the common means of communication between the ports of said surfaces and the cylinder, substantially as described. 75

2. The combination of a compressor-cylinder and piston, heads to said cylinder, a cylindrical cage structure for each head having independent series of ports, of which one series 80 opens to the interior of the cylinder, concentric annular valves operating on each cage structure for controlling the flow of fluid through independent sets of the ports thereof, and mechanism connected to the valves for operating the same, said ports from the cage structure to the cylinder being common to fluid passing either of the valves, substantially as described. 85

3. The combination of a compressor-cylinder 90 having heads each provided with independent chambers, a cylindrical cage in each head having independent series of ports opening respectively into said chambers, there being other ports between the interior of the cage 95 and the cylinder, with a cylindrical valve coacting with the ports between the cage and one of the chambers, and a second cylindrical valve coacting with the ports between the same cage and the second of said chambers, said valves 100 controlling the flow of fluid through the cage and being provided with means whereby they are operated, substantially as described.

4. The combination of a compressor-cylinder, heads thereto, each having two chambers, 105 one communicating with a receiver connection and the other communicating with the air or gas supply, a cylindrical cage within each head having two sets of ports communicating respectively with the said two chambers, and a 110 third set of ports connecting the interior of said cage with the cylinder, two annular valves operative upon the cage, each of said valves controlling the flow of fluid to one set of ports, with means for operating the valves, substantially 115 as described.

5. The combination of a compressor-chamber having connected with it a head including a structure provided with two series of ports formed respectively in two cylindrical surfaces thereof, there being a space between said two surfaces communicating with said ports, a pair of annular inlet and discharge valves constructed to respectively coöperate with the series of ports, said structure being provided 120 with a port connecting the space between its cylindrical surfaces with the interior of the cylinder, substantially as described. 125

6. The combination of a compressor-cylinder having heads, said heads each having two 130

cylindrical casings of different diameters and placed one within the other so as to form a cage, each casing having ports, there being also a port opening into the interior of the 5 said cylinder and connected to the space between said two casings, and sliding valves co-acting with the ports of said casings to control the flow of fluid through the latter port to and from the cylinder, substantially as described.

7. A compressor - cylinder having heads, each provided with a pair of substantially concentric cylindrical structures forming a cage, the space between said structures opening into 15 the cylinder, a series of ports in each struc-

ture opening into the space between the same, a piston-valve operating upon the inside surface of the inner of said structures and an annular valve operating upon the outer surface of the exterior one of said structures, the flow 20 of fluid to and from the cylinder being controlled by said valves, substantially as described.

In testimony whereof I have signed my name to this specification in the presence of two sub- 25 scribing witnesses.

EDWIN G. RUST.
